I claim the ornamental design for a:“three wheeled electric vehicle”, as shown.

DESCRIPTION

The claimed “three wheeled electric vehicle” is to be used for personal transportation in an industrial and/or a sporting environment.

FIG. 1 is a left front perspective view of a three wheeled electric vehicle showing my new design;

FIG. 2 is a left rear perspective view thereof; and,

FIG. 3 is a left side elevational view thereof, the right side being a mirror image of that side shown.
